UNITED STATES PATENT OFFICE.

HUBERT J. BRAUN, OF CHICAGO, ILLINOIS.

DESIGN FOR A LIGHTING-FIXTURE HUSK OR SIMILAR ARTICLE.

Application filed May 20, 1926. Serial No. 17,786. Term of patent 3½ years.

To all whom it may concern:

Be it known that I, HUBERT J. BRAUN, a citizen of the United States, and a resident of the city of Chicago, county of Cook, and State of Illinois, have invented a new, original, and ornamental Design for Lighting-Fixture Husks or Similar Articles, of which the following is a specification, reference being had to the accompanying drawing, forming a part hereof.

The drawing shows a perspective view of the lighting fixture husk or similar article.

I claim:

The ornamental design for a lighting fixture husk or similar article substantially as shown.

HUBERT J. BRAUN.
